UNITED STATES PATENT OFFICE.

ALVAR K. TERNSTEDT, OF NEW YORK, N. Y., ASSIGNOR TO PERFECT WINDOW REGULATOR COMPANY, OF NEW YORK, N. Y., A CORPORATION OF MAINE.

TENSION-ADJUSTING DEVICE FOR COUNTERBALANCE-SPRINGS.

1,215,589.

Specification of Letters Patent. Patented Feb. 13, 1917.

Application filed July 17, 1915. Serial No. 40,387.

To all whom it may concern:

Be it known that I, ALVAR K. TERNSTEDT, a subject of the King of Sweden, and a resident of New York, in the county of New York and State of New York, have invented certain new and useful Improvements in Tension-Adjusting Devices for Counterbalance-Springs, of which the following is a specification.

10 My present invention relates to a device or mechanism whereby the tension of springs used to counterbalance weight in a reciprocating mechanism may be adjusted.

15 The object of the invention is to provide a mechanism whereby the tension of the spring may be varied without the necessity of disassembling or taking apart any of the mechanism.

20 The invention is particularly useful in and adaptable for window regulator constructions wherein the window is raised and lowered by a driving mechanism comprising usually a chain and sprocket device embodying a coil spring used to counterbalance the weight of the window and assist in raising it. The invention is herein shown and described as applied to a window regulator of the type set forth in my prior application for patent for window operating 25 device filed Dec. 19, 1911, Ser. No. 666,759, but it will be understood that it may be employed in other types of window regulators as well as other mechanism wherein a part such as a window or sash is reciprocated 30 and provided with a counterbalancing spring for taking the weight of the part or assist in moving it without departing from the spirit of the invention.

35 The invention consists in the new and useful mechanism whereby the tension of a counterbalance spring may be varied as well as in the combinations of parts and details of construction hereinafter more particularly described and then specified in the 40 claims.

45 In the accompanying drawings Figure 1 is a front elevation of a window raising and lowering mechanism having my present invention embodied therein.

50 Fig. 2 is an enlarged front elevation of the lower sprocket of the mechanism shown in Fig. 1.

Fig. 3 is a vertical transverse section taken on the line 3—3 Fig. 2.

Fig. 4 is a partial section and side elevation similar to Fig. 3 but showing the parts in unlocked position.

Fig. 5 is a section through the sprocket wheel taken on the line 5—5 Fig. 3.

Fig. 6 is an elevation, parts being broken away, of the sprocket wheel shown in Fig. 2 but illustrating the reverse side from that shown in that figure.

Fig. 7 is a perspective view of the key used to rotate one part of the sprocket when adjusting the tension of the spring.

Referring to Fig. 1, the lower part of the window or part reciprocated is indicated at 1 while 2 indicates the lower part of the support or mounting thereof. 3 indicates a plate secured to the support 2 and is provided with a sprocket wheel 4 mounted thereon. A vertical depending bar or strip 5 is secured at its upper end to the plate 3 and at its lower end to a cross bar 6 secured to the mounting 2. The bar 5 constitutes a support for the lower sprocket 7, an endless driving chain 8 passing over the sprockets 4 and 7. The chain 8 is connected to the window by means of a pin 9 engaging in a slot 10 of a plate 11 secured to and depending from the window. By rotating a handle 12 connected to the sprocket 4 the chain 8 is caused to travel around the sprockets 4 and 7 and the window is raised or lowered according to the direction of rotation given the handle. These parts being fully described in my aforementioned prior application any further description herein is deemed unnecessary.

According to the present invention in the preferred manner of carrying it into effect, the lower sprocket 7 comprises two parts, one part 13 being dish-shaped and provided with teeth 14 around its periphery engaging the links of the chain 8 while the other part is in the form of a disk or cover 15. Disposed in the space between the parts 13 and 15 is a coiled spring 16 preferably of flat material, one end of which is secured to a lug 17 formed out of the material of the cover plate 15 by cutting a tongue therein and bending it laterally to the plane of the cover while the other end of the spring is se-

cured to a similarly formed lug 18 integral with the toothed disk 13. The outer end of the spring being secured to the toothed disk 13 travels with it while the inner end during the operation of the chain in raising and lowering the window is held fixed in a manner to be presently described.

When the window is lowered the spring 16 is wound up and stored with energy so that on raising the window it will unwind and assist in raising it by balancing its weight. In assembling the raising and lowering mechanism, the spring 16 is given an initial tension of an amount deemed necessary to balance the weight of the window but it frequently happens that after installing and operating the mechanism it is found that the tension of the spring is not correct to properly balance the window owing to various reasons such as variation in weight of windows, greater or less resistance in the guiding channels, &c. To meet this condition it is necessary to adjust the tension of the spring. This adjustment is made according to this invention without removing any of the parts or disturbing the mechanism as will be apparent from the following description.

19 indicates a ball race forming a hub on which the toothed disk 13 rotates, a set of balls 20 being interposed between the hub and a flange of the disk. The ball race 19 is securely fastened to the cover plate 15 by screws 21.

35 The bar 5 is provided with a hole 22 into which any one of a plurality of annularly arranged projections 23 on the face of the cover plate 15 is adapted to fit so that when the cover is brought into such position that a projection 23 enters the hole 22 and the cover fastened in this position, the cover and the hub 19 are locked to the supporting bar 5 and are immovable but still the toothed disk 13 is left free to rotate on the hub 45 when the chain 8 is caused to travel. By providing a plurality of projections 23 closely spaced, the cover 15 can be locked in most any desired position and when the projections are arranged in a complete circle 50 as shown a coöperating hole 22' is provided in the bar 5 to receive the projection diametrically opposite the one in the hole 22.

24 indicates a locking key passing through the ball race hub 19, cover 15 and bar 5 and is provided with a head 25 bearing against the face of the hub 19. The other end of the key is threaded and provided with a nut 26 whereby the hub 19, cover 15 and supporting bar 5 are secured together and 60 when a projection 23 is in the hole 22 the cover 15, to which the inner end of the spring is attached, is locked to the support 5 and immovable.

Upon loosening the nut 26 the sprocket wheel in its entirety can be forced laterally

into the position shown in Fig. 4 in which position the projections 23 are out of the holes 22 and 22' and the cover 15 and therefore the inner end of the spring 16 may be rotated in any desired manner. The toothed disk 13 and therefore the outer end of the spring being held by the position of the window and chain 8 any rotation given the cover will vary the tension of the spring either increasing or decreasing it according to the direction of rotation. Any desired variation may be made and the parts clamped in the adjusted position by causing the projections 23 to enter the holes 22 and 22' in the bar 5 and tightening the nut 26.

To provide a ready means for rotating the cover, I preferably form two diametrically opposed lugs 27 on the shank of the key 24 and provide a slot 28 in the end of the shank for the insertion of a screw-driver. The lugs 27 fit into suitably formed recesses 29 in the hub 19 and cover 15 and when the projections 23 have been removed from their holes in the bar 5, a screw-driver in the slot 28 readily rotates the hub and cover by means of the lugs 27 on the key. It will thus be seen that the tension of the spring 16 may be varied at will without removing or operating the raising and lowering mechanism, detaching the sprocket from its support or disassembling any of the parts of the mechanism.

30 indicates laterally projecting lugs formed out of the material of the cover 15 and in such position that they are annularly arranged around the ball race 19 at a slight distance therefrom. The object of these lugs or stops is to prevent the spring being wound so tight that it will bind the ball race.

It will be understood that the invention is not limited to use in constructions of the type shown and described nor to the specific arrangements shown for carrying the invention into effect except as may be specified in the appended claims.

What I claim as my invention is:—

1. In a mechanism of the character described, the combination of a movable part, means for reciprocating said part and comprising a two-part wheel, a fixed support on which said wheel is rotatably mounted and a coil spring having an end connected to each part of said wheel, an annularly arranged pin and slot device for adjustably securing one part of said wheel to said support and a key for rotating said part and clamping it to said support in adjusted position.

2. In a mechanism of the character described, the combination with the window, of raising and lowering means for the same and embodying a two-part wheel, a coil spring having one of its ends connected to one part of said wheel and its other end to

the other part, one part of said wheel being operated by said means and the other being secured to a fixed support by a pin and slot connection and a key by which said part 5 may be rotated and clamped to its support.

3. In a mechanism of the character described, the combination with the window, of a chain drive for operating the same and embodying a two-part sprocket wheel one 10 part of which is operated by the chain and the other part being provided with a plate and a hub on which said chain part rotates, a fixed support for said wheel, an annularly arranged pin and slot device whereby said 15 plate may be held to said support at a number of adjusted positions, a coil spring having one of its ends connected to one part and its other end to the other part of said wheel and means for rotating said plate and hub independent of the other part of the wheel 20 to adjust the tension of said spring.

4. In a mechanism of the character described, the combination with the window,

of a chain drive for operating the same and embodying a two-part sprocket wheel one 25 part of which is operated by the chain and the other part being provided with a plate and a hub on which said chain part rotates, a fixed support for said wheel, an annularly arranged pin and slot device whereby said 30 plate may be held to said support at a number of adjusted positions, a coil spring having one of its ends connected to one part and its other end to the other part of said wheel and a key adapted to rotate said plate independent of the sprocket part of said wheel to adjust the tension of said spring and to also clamp said plate in adjusted position to its support.

Signed at New York, in the county of 40 New York and State of New York, this 12th day of July, A. D. 1915

ALVAR K. TERNSTEDT.
